UNITED STATES PATENT OFFICE

GEORGE L. BEERS, OF WILKINSBURG, PENNSYLVANIA, ASSIGNOR TO WESTINGHOUSE ELECTRIC & MANUFACTURING COMPANY, A CORPORATION OF PENNSYLVANIA

RADIO RECEIVING DEVICE

Application filed February 10, 1925. Serial No. 8,210.

My invention relates to radio receiving devices and particularly to radio receiving devices of the type comprising a loop antenna.

An object of my invention is to provide an improved radio-receiving device comprising a loop-antenna and a cabinet, the cabinet being so constructed as to permit storage therein of the loop-antenna when the device is not in operation.

Another object of my invention is to produce a convenient, demountable loop-antenna.

Another object of my invention is to produce a rotatable loop antenna which may be easily demounted from its support.

Another object of my invention is to provide, in a radio-receiving system of the type comprising a rotatable and demountable loop-antenna, means whereby the use of flexible conductors, between the loop-antenna and the additional apparatus, shall be avoided.

In the construction and operation of radio receiving sets, it has been customary to combine certain systems of radio receiving apparatus with loop antennae. This combination has usually been made by placing the loop and the receiving apparatus upon a convenient table and making a connection between the loop and the additional electrical units by means of flexible wire leads. This combination has been bulky and clumsy. Only under special conditions has the loop been conveniently rotatable to change the plane of reception from station to station, and while the loop structure has occasionally been constructed to be folded into a presumably more compact structure, convenient storage means have been lacking.

According to my invention, I so support the electrical units, constituting a radio receiver, from the inner surface of one of the walls of a radio-cabinet, that sufficient space exists between the said units and the other walls of the cabinet to accommodate a loop-antenna when the receiver is not in use. In addition, I provide a device for rotatably supporting the loop exteriorly of the cabinet when the receiver is in use, the said supporting device being so constructed and

mounted that it is capable of being retracted into the cabinet when not in service.

Other objects and structural details of my invention will be apparent from the following description, when read in connection with the accompanying drawings, wherein:

Figure 1 is a view in front elevation of an embodiment of my invention, and

Figure 2 is a fragmentary view in vertical section of the same embodiment, substantially on the line 2—2 of Fig. 1.

In the drawing, a cabinet 1 has attached to the front thereof, a panel 2 upon which are mounted the proper dials and control devices as indicated. The rear portion of the cabinet 1 is provided with hinged door portions 3 and 4 adapted to be swung open and to permit access to the interior of the case. The customary triode vacuum tubes 5 and associated coils and transformer apparatus 6 are mounted upon a base plate 7 supported from the panel 1 by a bracket 8, thereby leaving a clear unencumbered space around the entire periphery of the apparatus and within the margin of the cabinet. A loop antenna 9 is constructed of a size suitable for insertion within this space.

The loop 9 is constructed with a journal bearing 11 at the approximate center of its lower cross member and is provided with a wire winding 10. A pivot shaft 12, adapted to cooperate with journal 11, is slidably mounted within the case 1 and is arranged to be projected upwardly through the top thereof. The shaft 12 is adapted to be held in either projected or withdrawn position by a locking device comprising a set-screw 14. A plurality of contact sleeves 15, 16 and 17 are provided upon the upper end of the shaft 12 to which connection is made by leads 18 that are also connected to the amplifying and detecting apparatus 5 and 6. The loop 9 is provided with a brush holder 19 upon which are mounted brushes 20, 21 and 22, from which connection is made to various portions of the wire 10 wound upon loop frame 9.

In the operation of my device, the loop may be inserted within the case 1 in the course of preparation for shipment thereof. It re-

mains in this position during such periods of storage and non-use as may be desirable, and it is adapted to so fit with sufficient closeness that there is little shaking or danger of breakage during shipment. When it is desired to operate the apparatus, the panel portions 3 and 4 of the case 1 are opened and swung back, whereupon the loop 9 is conveniently accessible and may readily be withdrawn from its storage position. With the loop withdrawn, the setscrew 14 and the shaft 12 become conveniently accessible and the shaft 12 may be pushed upward into operative position and held there by the setscrew 14. The panels 3 and 4 of case 1 may then be closed to restore protection from dust and injury to the contained radio apparatus.

The bearing 11 of loop 9 may then be fitted over the shaft 12 and allowed to slide down until stopped by the surface of the top of the case 1, in which position register is obtained between the brushes 20, 21 and 22 and the contact thimbles 15, 16 and 17. Upon energization of the triodes 5 within the apparatus, such signals as are being transmitted with sufficient strength may be received upon the apparatus, and undesired stations may be excluded by suitable tuning of the apparatus and by suitable rotation of the loop 9.

Upon the completion of the reception of the desired signals, the loop 9 may be returned to its storage place by a reversal of the sequence of the operations described for the preparation of the apparatus for operation.

Although I have illustrated and described only a single embodiment of my invention many modifications thereof will be apparent to those skilled in the art to which it pertains. My invention, therefore, is not to be limited except in so far as is necessitated by the prior art or by the spirit of the appended claims.

I claim as my invention:

1. In a radio receiving system, a loop antenna, a cabinet, a receiving set within said cabinet and supported wholly from one wall thereof and closable openings in the opposite wall of said cabinet through which said loop may be passed, the receiving set being spaced away from the remaining walls of the cabinet sufficiently to permit the loop antenna to be inserted into the cabinet in a position surrounding the receiving set.

2. In a radio receiving system, a loop antenna, a cabinet, a receiving set within said cabinet and supported wholly from one wall thereof, the opposite wall of the cabinet having openings, closures for said openings, the size of the openings being sufficient to permit the passage of the loop antenna when the closures are open, the receiving set being spaced away from the remaining walls of the cabinet sufficiently to permit the loop antenna to be inserted into the cabinet in a position surrounding the receiving set.

3. In a radio receiving system, a loop an-

tenna, a cabinet, receiving apparatus within said cabinet and supported wholly from one wall thereof, the opposite wall of the cabinet having openings provided with movable closures, the size of the openings being sufficient to permit the passage of the loop antenna when the closures are open, the receiving set being spaced away from the interior of the cabinet sufficiently to permit the loop antenna to be inserted into the cabinet in a position surrounding the receiving apparatus, and an antenna-supporting device mounted in the interior of said cabinet and being adapted to be partially withdrawn therefrom.

4. A radio receiving system comprising a cabinet having a front wall, receiving apparatus within said cabinet supported wholly from said wall and spaced away from the remaining walls, a loop antenna, said cabinet being provided with movable closures of sufficient size to permit said loop to be inserted into said cabinet in a position surrounding said receiving apparatus or withdrawn therefrom, and separable means for mounting said loop exteriorly on said cabinet.

5. A radio receiving system comprising a cabinet having a front wall, receiving apparatus within said cabinet supported wholly from said wall and spaced away from the remaining walls, a loop antenna, said cabinet being provided with movable closures of sufficient size to permit said loop to be inserted into said cabinet in a position entirely surrounding said receiving apparatus or withdrawn therefrom, and separable means for rotatably mounting said loop exteriorly on said cabinet, said means comprising devices for electrically connecting said loop to said receiving apparatus.

6. A radio receiving system comprising a cabinet having a front wall, receiving apparatus within said cabinet supported wholly from said wall and spaced away from the remaining walls, a loop antenna, said cabinet being provided with movable closures of sufficient size to permit said loop to be inserted into said cabinet in a position surrounding said receiving apparatus or withdrawn therefrom, and a loop-supporting device slidably mounted in said cabinet and adapted to be withdrawn partially therefrom, said supporting device and said loop being provided with separable cooperative elements for connecting said loop electrically to said receiving apparatus.

In testimony whereof, I have hereunto subscribed my name this 3rd day of February, 1925.

GEORGE L. BEERS.
